UNITED STATES PATENT OFFICE.

JOHN A. KATZENMEYER, OF ELLWOOD CITY, PENNSYLVANIA.

REDUCING CYLINDRICAL BODIES.

Application filed June 5, 1922. Serial No. 566,084.

To all whom it may concern:

Be it known that I, JOHN A. KATZENMEYER, residing at Ellwood City, in the county of Lawrence and State of Pennsylvania, a citizen of the United States, have invented or discovered certain new and useful Improvements in Reducing Cylindrical Bodies, of which improvements the following is a specification.

In an application filed June 5, 1922, and numbered serially 566,083, is described a method of reducing articles in which the reducing element moves in a plane at an angle to radii extending through the points of contact of the element with the article, such angle being obtuse at the initial point of impact but decreasing to a right angle at the point where reducing elements cease to be effective. In the method described herein the plane of movement of the reducing element is parallel with or at a very obtuse angle to the radii and maintains such relation during its engagement with the article. The invention is hereinafter more fully described and claimed.

In the accompanying drawings forming a part of this specification, Fig. 1 is an elevation showing two reducing heads in operative relation to a hollow article; Fig. 2 is a view partly in elevation and partly in section showing four heads arranged around a hollow article; Fig. 3 is a diagrammatic view illustrating one manner in which the head or heads operate and Fig. 4 is a similar view illustrating a modification of the method shown in Fig. 3.

In the practice of the invention suitable mechanism, such for example as that shown in application Serial No. 566,083 above referred to, is employed for controlling the rotary and longitudinal movements of the article being operated on. The reducing elements or members consist of a plurality of heads arranged circumferentially around the line of movement of the article each head consisting of a disc 1 secured to a shaft 2 and having a recess in one side for the reception of the boss 3 of the annular member 4 as shown in Fig. 2. This member is peripherally grooved for the reception of balls 5 formed of hard steel or material suitable for the purpose. The balls are held within the groove or raceway by an annular plate 6, provided with an externally threaded rib 7 screwing into a recess in the outer face of the member 4. The portion of the plate with-

in the rib is undercut so as to form with the front face of the plate 6 an annular V-shaped channel 8 for the reception of a lubricating or cooling fluid, which is supplied by a pipe 9 extending from any suitable source of supply. The heads, when operated, are rotated at a high speed so that the fluid will collect in the groove 8, and be forced therefrom by centrifugal force through passages 10 which connect with the raceway in the rear of the balls. As the heads are rotated at a high rate the jets of fluid will be under a high pressure and will not only prevent the entrance of scale, etc., between the balls but will tend to force the balls outwardly.

In practice, two or more of these heads are circumferentially arranged around the line of movement of the article. As shown in Fig. 3 the heads may be so supported that planes passing through the centers of the balls will coincide with the axis of the article or so that such plane will form an acute angle, with the axis of the article as shown in Fig. 4. When the heads are arranged as shown in Fig. 3 the balls will effect a longitudinal flow of the article accompanied by a slight lateral displacement of the metal. In order to prevent a mere longitudinal grooving or scoring of the article, provision is made for the rotation of the article, preferably by means described and shown in the application hereinafter referred to which is adapted to apply a constant rotative pressure to the article. This pressure being constant and the contact of the balls with the article being intermittent, the article will move spirally, so that as in the method set forth in said application, the flow of metal will be spirally of the tube, and the longitudinal component of the spiral will be greater than the transverse component.

It will be understood that in the practice of the invention the movements of the article are so controlled that the amount of metal displaced by the individual balls will be small, it being preferred that the feed be so regulated that the metal is displaced in a manner closely analogous to that occurring in the spinning of metals, as the balls will be carried along at a rate greater than the peripheral movement of the balls, and there will be a combined rolling and spinning action.

When the heads are arranged as shown in Fig. 4, so that their planes of rotation will be at an angle to the axis of the article, the

rotation of the heads will tend to rotate the article, such tendency increasing with the angle between the planes of rotation and the axis of the article. In such case it will be 5 preferred that the rotation of the article should be determined by the feed mechanism.

I claim herein as my invention:

1. A mechanism for reducing a cylindrical body having in combination means for rotating and moving said body longitudinally, a head adapted to rotate in a plane approximately coincident with the axis of the article and provided with a peripheral raceway and 15 a plurality of spherical elements arranged in the raceway.

2. A mechanism for reducing a cylindrical body having in combination means for rotating and moving a body longitudinally, 20 a plurality of heads provided with a peripheral raceway, a plurality of spherical reducing members, said heads being so supported that its plane of revolution will maintain a

constant relation to radii passing through points of impact of the reducing members 25 with the body being reduced.

3. The method herein described of reducing cylindrical bodies which consists in rotating and moving said body longitudinally and subjecting it to the successive impacts 30 of a plurality of spherical elements moving in a plane having a fixed relation to radii passing through the points of impact of said elements with said body.

4. The method herein described of reducing cylindrical bodies which consists in rotating and moving said body longitudinally and subjecting it to the impact of a plurality 35 of spherical elements moving in the direction of the movement of the body at the instant 40 of impact in a plane having a fixed relation to radii passing through the points of impact of said elements with said body.

In testimony whereof, I have hereunto set my hand.

JOHN A. KATZENMEYER.
